CLAIM

The ornamental design for a shopping cart, as shown and described.

DESCRIPTION

FIG. 1 is an isometric view of a shopping cart according to an embodiment of the invention, with elements in dashed lines forming no part of the claimed design.

FIG. 2 is a front view of a shopping cart, according to an embodiment of the invention, with elements in dashed lines forming no part of the claimed design.

FIG. 3 is a rear view of a shopping cart, according to an embodiment of the invention, with elements in dashed lines forming no part of the claimed design.

FIG. 4 is a right side view of a shopping cart, according to an embodiment of the invention, with elements in dashed lines forming no part of the claimed design and with a left side view being a mirror image of the right side view.

FIG. 5 is a top view of a shopping cart, according to an embodiment of the invention; and,

FIG. 6 is a bottom view of a shopping cart, according to an embodiment of the invention, with elements in dashed lines forming no part of the claimed design.

1 Claim, 6 Drawing Sheets
